COMBINED COMB AND RAZOR

Anthony Battaglia, 17030 NE. 21st Ave.,
Miami, Fla. 33162

Filed Aug. 18, 1966, Ser. No. 3,520

Term of patent 14 years

(Cl. D86—8)

FIG. 4

FIG. 1

FIG. 2

I claim:

The ornamental design for a combined comb and razor, substantially as shown and described.
